UNITED STATES PATENT OFFICE.

HERBERT M. CHANEY, OF SARDINIA, OHIO.

BELT-SUPPORT.

1,299,680.

Specification of Letters Patent.

Patented Apr. 8, 1919.

Application filed November 1, 1916. Serial No. 128,991.

To all whom it may concern:

Be it known that I, HERBERT M. CHANEY, a citizen of the United States, residing at Sardinia, in the county of Brown and State 5 of Ohio, have invented certain useful Improvements in Belt-Supports, of which the following is a specification, reference being had therein to the accompanying drawing.

The invention relates to belt supports, and 10 more particularly to the class of invisible belt supports for use in trousers.

The primary object of the invention is the provision of a support of this character wherein the belt can be conveniently supported 15 interiorly of the trousers near the waist line thereof without causing discomfort to the wearer and at the same time sustaining the trousers in proper position and avoiding the working out of the body garments therefrom.

Another object of the invention is the provision of a support of this character wherein the same can be readily applied interiorly of the trousers so as to be invisible from 20 without and will hold the belt in proper position so as to avoid the riding of the belt over the waist line of the trousers or the sagging of the trousers at the waist line and also eliminating any discomfort to the 25 wearer.

A further object of the invention is the provision of a support of this character wherein the construction thereof is novel in form so that it can be readily applied 30 to or removed from the trousers and when applied will properly support the belt so that the same will be invisible and arranged interiorly of the trousers, the belt being readily removable from the support or permanently attached thereto.

A still further object of the invention is the provision of a belt support of this character which is extremely simple in construction, thoroughly reliable and efficient in its 45 purpose, strong, durable, applied to and removed from the trousers with despatch and inexpensive in manufacture.

Other objects will be in part obvious and in part hereinafter set forth.

The invention accordingly consists in the features of construction, combination of elements and arrangement of parts which will be exemplified in the construction herein- 50 after described, and the scope of the application of which will be indicated in the appended claims.

In the accompanying drawings:

Figure 1 is a fragmentary perspective view of trousers open, showing the belt support constructed in accordance with the invention applied, with the belt therein; 60

Fig. 2 is a fragmentary vertical sectional view through the trousers and belt;

Fig. 3 is a perspective view of the belt support; 65

Fig. 4 is a vertical sectional view on the line 4—4 of Fig. 2.

Similar reference characters indicate corresponding parts throughout the several 70 views of the drawings.

Referring to the drawings in detail, A designates the upper portion of trousers which are of the ordinary well known construction, and B the belt, which may be of the elastic or non-elastic type, and is adapted to be fastened about the waist of the user in any suitable manner. The belt B is removably held within a plurality of detachable supports C, each of which is herein- 75 after fully described.

Each support comprises a strip of material, preferably metal, having the required rigidity and slight resiliency, which is bent on itself to form a substantially U-shaped major portion constituting a loop 10 for the 80 reception of the belt B, the ends of the limbs of the loops being inwardly curved to provide ears 11 and 12 respectively, the ears being formed with eyes 13 at opposite edges thereof which diverge inwardly from each other, while the eyes on the ear 12 are positioned in alinement and in close relation with the adjacent faces of the eyes on the ear 11 so as to maintain the ears against 85 relative movement. Adapted to be engaged in these eyes 13 is the pin member 14 of a safety pin 15 which is of the ordinary well known construction. The safety pin 15 is engaged in the waist band of the trousers A as is clearly shown in Figs. 1 and 2 of the 90 drawings, with the pin member 14 engaged in the eyes 13 to overlie the ear 12, thereby sustaining the ears in close relation to each other, the ear 12 being formed with an in- 95

bent portion 16 which constitutes a shoulder 100 and in this manner the loop portion 10 of the support C is closed to sustain the belt B therein. It is, of course, understood that a plurality of the supports C are fastened at the desired intervals interiorly of the 105 trousers A and have trained the belt B there- through for supporting the same within the 110

trousers so that both the supports C and the belt B are invisible when in use. The ordinary belt can be worn with the trousers exteriorly thereof in the usual manner, if desired.

It will be apparent that the supports C can be readily detached from the trousers A and also that the belt B can be removed from said supports, thereby enabling the supports 10 and belt to be employed with different trousers, as the occasion may require.

It is to be understood that the invention is not restricted to any particular means of fastening the support to the trousers or the 15 belt within the support, as changes, variations and modifications may be made in the invention such as come properly within the scope of the appended claims without departing from the spirit of the invention or 20 sacrificing any of its advantages.

Having thus described my invention, I claim:

1. The combination with a belt, of a support comprising a hanger for engagement 25 with the belt and formed from a single piece of material bent upon itself and having the folded portions offset to provide a recess

therebetween for receiving the belt, the upper portions of said support constituting ears curved upwardly and outwardly from 30 the hanger and provided at their terminals with pin engaging means, and a safety pin engaged by said means and adapted for detachable engagement to a garment.

2. A belt support comprising a hanger 35 formed from a single strip of material folded medially of its ends having one of the folded portions offset to form an open loop for removably receiving a belt, ears continuing from the folded portions and curved 40 upwardly and outwardly therefrom, eyes formed on the opposite edges of the ears near the terminals thereof, the eyes on one of the ears being arranged in close relation and against the adjacent faces of the eyes 45 on the other ear and being alined therewith and a safety pin adapted for detachable engagement with a garment and having its pin member detachably engaged in the eyes for closing the loop and suspending the 50 same from said safety pin.

In testimony whereof I affix my signature.

HERBERT M. CHANEY.
